UNITED STATES PATENT OFFICE

WILLIAM E. WINE, OF TOLEDO, OHIO

VENTILATOR FOR CARS

Application filed July 10, 1929. Serial No. 377,200.

My invention relates to new and useful improvements in ventilators for cars, such as grain cars, cars in which flour is to be shipped, and other types of cars that should be ventilated.

As is well known to those skilled in the art, a part of the grain or flour is often spoiled when shipped in cars, due to the fact that there is a certain amount of moisture in the grain or in the other products in the car and, when the hot sun beats upon the roof of the car, the moisture will condense on the inner surface of the roof or, in other words, the roof will sweat and the water will drop down onto the flour or the containers holding the flour or onto the grain and thereby cause considerable loss or damage.

One of the objects of the present invention, therefore, is to provide ventilators, each with but one shutter, which are located near the opposite diagonal corners of the car and up as near the roof as possible, so that a draft of air may pass over the grain or flour and from one end of the car to the other to thus prevent any sweating of the roof and the spoiling of the grain or flour within the car.

Still another object of the invention is to provide a ventilator of relatively small dimension comprising simply a frame and one louver or shutter and means connected to the outer edge of the shutter whereby the same may be conveniently and quickly locked in either its open or closed position.

Most of the freight car ventilators which are used today are placed in cars where fresh or perishable products are used and the car is to be ventilated throughout its length and breadth. In the present instance, however, the invention contemplates using ventilators located just near the top of the grain or freight cars, so that a draft may simply pass over the load within the car.

Still another object of the invention is to provide a ventilator with a special form of supporting means or a locking bar for the shutter, together with a special form of frame whereby it will be impossible for the lower end of the supporting bar to slip from without the frame, even though the locking pin is not inserted.

Still another object of the invention is to provide a form of ventilator of special type and to so position the same in a grain car that it will absolutely prevent any sweating of the car and thus save considerable damage or loss to the grain within the car.

Still another object of the invention is to provide an exceedingly simple type of ventilator having but one shutter and having a special form of frame and locking bar, so that the shutter may be conveniently locked in either the open or closed position by the use of a locking pin, but should even the locking pin fail to be used, the shutter is so constructed that it will be securely held either in its open or closed position.

With these and other numerous objects in view, the invention consists in certain new and novel arrangements and combination of parts, as will be hereinafter more fully described and pointed out in the claims.

Referring now to the drawings showing an embodiment of the invention,

Fig. 1 is a side elevation, of a schematic nature, of a car;

Fig. 2 is a horizontal section, of a schematic nature, showing the car;

Fig. 3 is an enlarged side elevation of one corner of the car;

Fig. 4 is a sectional view taken substantially through the line 4-4 on Fig. 7 with the shutter removed for the sake of clearness;

Fig. 5 is a similar view but with the shutter in place;

Fig. 6 is an enlarged front view of the ventilator showing the shutter in its closed position;

Fig. 7 is a sectional view of the ventilator showing the shutter in its closed position;

Fig. 8 is a similar view showing the shutter in its open position;

Fig. 9 is a perspective of the locking bar.

Referring now more specifically to the several views, and for the moment to Fig. 1, there is shown schematically a grain car 1 with the usual grain doors 2, the roof 3, the ladder 4 on one side of the car and the ladder 5 on the other side of the car (see Fig. 2). The sides 6 and 7 of the car are unbroken

with the exception of the doors 2, while likewise the ends 8 and 9 of the car are unbroken.

However, as may be seen in Fig. 1, I position a small ventilator 10 near the ladder 4 directly beneath the roof, and in a like manner, position a further ventilator 11 on the opposite side 7 of the car and in the relative same position as the ventilator 10.

It will be understood that grain cars are packed nearly to their capacity, but not up to the plane in which these ventilators are located, and by so positioning these ventilators about to be described, it will permit a circulation of air over the top of the grain and thus prevent any sweating or dropping of moisture from the roof of the car when the moisture condenses. I thus prevent the damage to the grain or flour that would otherwise occur in a nonventilated car.

In the same manner, if flour is shipped in the car and the barrels are piled one upon the other, they will not reach up to the plane of these ventilators and the air may circulate through these ventilators and thus prevent any sweating and resultant damage to the flour.

Having thus described the desired location of the ventilators and the purpose for which they were invented, more specific reference will be made to their structure and the manner in which they operate.

It might be mentioned here, however, that the location of the ventilators and the manner of ventilating the car form the subject matter of a divisional application filed by me on February 26, 1930 and bearing Serial Number 431,500.

Referring now more specifically to Figs. 3 to 9 inclusive and for the moment to Fig. 6, there will be seen one of these ventilators 10 and it will be noticed that it comprises a rectangular frame 12, while on the respective side pieces 13 of the frame, there may be seen the two wings or extension plates 14, which may be scalloped, as at 15, and are provided with the opening 16 to receive the bolts that hold the ventilator to the sides of the car.

Referring now to Figs. 7 and 8, it will be seen that the frame is provided with a top bar 17, which is also provided with the opening 18 for the bolts, while a bottom rail 19 is also formed integral with the frame and with the wings 14, this rail being also provided with openings 20, so that the frame may be bolted on all four sides to the car, as shown in Fig. 3. In Figs. 4 and 5, I have shown a horizontal sectional view of the ventilator and the manner in which the side 6 of the car may be cut out as well as the inner sheathing 21, the frame being then fitted within the opening and securely bolted into place.

Referring again to figs. 7 and 8, the back wall 22 of the frame may be seen to extend from a plane even with the top rail 17 down

to the point 23 where it slopes downwardly, as at 24, to the point where it merges, as at 25, with the lower rail 19.

As is also shown in Fig. 8, a water-proof paper 26 may be placed in front of this lower rail and likewise a filler 27 is shown between the siding and the ventilator.

Still glancing at Figs. 7 and 8, there will be seen directly beneath the top rail 17 a projection 28 with the downwardly projecting rim 29, this small roof-like projection fitting under the siding of the car and projecting over the shutter of the ventilator, which shutter will be shortly mentioned. In a like manner, resting upon the lower wall of the cut-out portion of the side of the car may be seen a bottom or floor 30 of the ventilator which likewise has its extreme edge 31 projecting downwardly and over the siding.

As far as the invention has been disclosed, it will be seen that the front or top rail 17 and the bottom rail 19 as well as the two side wings 14 are all in the same plane, a portion of the frame extending in front of this plane to be enclosed within the siding of the car, while the remainder of the frame is behind this plane and is enclosed within the car. Thus, the frame may be bodily placed within the opening in the siding from the inside of the car and then tightly bolted in place by the series of bolts 32, as may be clearly seen in Fig. 3. It will also be seen that when the ventilator frame is once in place, it will be rigidly held and, at the same time, the walls about the opening will be well protected from any rain and thus will not tend to rot.

It will still further be seen that the major part of the frame is within the car and when the shutter about to be described is in its closed position, there is but a slight projection beyond the outer surface of the car, this projection simply being the end of the locking bar and the lower edge of the shutter.

The upper portion of the frame is in the form of a longitudinal chamber which extends from one side of the ventilator to the other but, as may be seen in Figs. 7 and 8, there is no bottom for the chamber. On the other hand, small supporting lugs 33 are provided, so that a metal screen 34 may be within the chamber and rest on these lugs, the upper edge of the screen fitting under lugs 35 which may also be seen in Fig. 6. The upper row of the bolts 32 will project over the screen so that the screen, after once being slipped down in position, will remain there until it is desired to take the same out and clean it. By providing a chamber and small screen of this nature, any dust or cinders that would otherwise enter the car and mix with the grain or the flour will be caught in the screen and likewise any material from the car will not fall down into the ventilator frame and thus jam or prevent the shutter from operating.

On the side walls of the frame 13, there may also be seen the small arcuate tracks or lugs 36, which act as a guideway for the louver or shutter 37, shortly to be described 5 in detail.

On the inner surface of each of these side or end pieces, there are formed the two small pivot bearings 37' which are the center points from which the arcuate tracks 36 are struck. 10 Also extending across the ventilator from one side to the other is the small downwardly extending ledge 38, while rearwardly of the same and also extending entirely across the rear wall of the frame is the small ledge 39 15 and, as may be seen, the larger of the tracks 36 extends from the one wall 38 to the ledge 39 to thus brace the same.

Referring now for the moment to Fig. 6, there will be seen formed centrally of the 20 frame the two guideways or tracks 40, which have the inwardly extending lips or lugs 41 at their outer ends, these guideways running from a point just beyond the inner edge of the frame upwardly and rearwardly to the small 25 wall 39, just heretofore mentioned.

Now having described the frame, the shutter and the locking bar will next be described.

It might be mentioned here that the shutter and frame in their broadest aspect are of the 30 well known Wine type, as shown in Patents, Nos. 1,298,136, granted to me March 25, 1919, 1,359,556, granted to me November 23, 1920, and 1,040,083, granted to me October 1, 1912.

It will be seen that the shutter comprises 35 the two side pieces 42 which are formed integrally with the arcuate face or closure 43. The side pieces are reduced at their lower extremities and are provided with the trunnions 44, which rest in the previously mentioned 40 bearings 37'.

As may be also seen in Fig. 6, there may be provided ribs 45 on the under surface of the shutter wall to brace the same, while additional metal is allowed to flow, as at 46, to 45 provide strength where the side pieces merge with the shutter or closure wall 43.

The closure wall 43 also extends slightly outwardly beyond the side pieces 42, as at 47, and these projections, it will be understood, 50 come within the tracks formed by the arcuate ribs 36 formed on the inner portion of the side pieces of the frame to thus prevent the same from jarring out of position. The shutter is also provided in its central portion and 55 on its outer edge with the two lugs 48, as also shown in my previous patents, and between these lugs is fastened one end of a locking bar 49. The shutter per se is identical with the shutter shown in my previous patents 60 mentioned.

Before describing this locking bar, it will be understood that the shutter, as in my previous patents, may be swung rearwardly, as shown in Fig. 7 to thus close the ventilator, 65 or it may be swung to the position as shown

in Fig. 8 to thus open the ventilator and allow the air to pass beneath this shutter, up through the small screen 34 and up through the chamber into the car.

Now for operating and holding the shutter, I use a special type of locking bar, for which special provisions have been made in the frame, as heretofore mentioned. It will be noticed that this bar 49 comprises the body portion 50 with the downwardly extending arm 51 (see Fig. 9), while at its rear end, there is provided the enlarged elongated cylindrical portion or trunnion 52. It will also be noticed that this trunnion 52 is provided with the opening 53 therethrough. Likewise, the forward end of the body portion is provided with an opening 54 as well as the arm 51 with the opening 55.

This locking bar may be ribbed, as at 56 and 57, to thus provide a relatively light but 85 strong bar.

It might be here mentioned that the frame, the shutter and likewise this locking bar are all castings, therefore, necessitating but little 90 machining or skilled labor thereon.

Now looking at Figs. 6 to 9 inclusive, it will be seen that the forward end of the bar is permanently pivoted through the opening 54 to the lugs 48 of the shutter. The rear end of the bar with the trunnion 52 fits within the guideways 40 and, when the shutter is in its closed position, a pin 58 is passed through openings 59 in the ends of the guideways 40, through the opening 53 in the trunnion 52, and thus locking the shutter in its closed position. It will also be seen that even should this pin be not inserted, after the locking bar is once in position it cannot swing out of the frame, because the trunnion 52 will be held by the lips 41 at the ends of the guideways 40.

When the shutter is in its open position, the same will be swung to the position shown in Fig. 8, the pin 58 having, of course, been removed and the rear end of the locking bar will travel upwardly and impinge against the wall 39, as shown in Fig. 8. The pin 58 may now be passed through the opening 55 in the arm 51 of the locking bar, thus tightly locking the shutter in its open position.

In this case also, should the pin not be inserted, the weight of the shutter and the way it is mounted will keep the same open and the trunnion 52 bearing against the wall 39 of the frame will prevent the shutter from dropping to an unnatural position.

Thus, it will be seen that the rear end of the locking bar is arranged to cooperate with the wall 39 and with the lips 41, and even though the pin be not inserted in either instance, the shutter will remain where placed until again changed.

From the foregoing, it will be seen that I have provided a ventilator comprising a novel frame together with one of my old types of shutters and with a new form of lock-

ing bar, thus providing a ventilator of extremely simple construction. Also, I have provided a ventilator that is quickly and easily assembled, easily installed, and may be quickly and easily operated to either one of its positions.

It will be understood that although this ventilator is especially adapted for grain cars or for cars carrying flour or even for cars carrying perishable products, it may also be used with other structures where a simple, small and efficient ventilator is desired and wherein it will be impossible for anyone of evil bent to enter the same.

Lastly, it will be seen that after the patterns have once been made, the castings may be made at a relatively low cost and the entire ventilator assembled on a cheap, commercial scale.

Having thus described my invention, what I claim as new and desire to secure by Letters Patent is:

1. A ventilator for railway cars comprising a frame, said frame having an air passageway therethrough, a rockable shutter for opening and closing said passageway, a bar connected to the upper edge of said shutter, said bar being lockable to the frame when the shutter is in its open and closed positions, and means for retaining one end of the bar always within the frame.

2. A ventilator for a freight car comprising a frame, said frame having a restricted opening therethrough, a shutter rockably mounted in said frame to open and close said opening, a bar pivotally mounted to one edge of the shutter, said bar provided with a downwardly extending arm, and means for locking the lower end of said arm or the free end of said bar to said frame to thereby hold the shutter in its open or closed position, respectively.

3. A ventilator for freight cars comprising a rectangular frame in the form of a housing, means projecting outwardly from the frame and adapted to fit within an opening, said housing having a passageway therethrough, a shutter mounted in front of said passageway and rockable to open and close said passageway, a bar provided with an arm extending angularly therefrom, one end of said bar being pivotally secured to said shutter, a guideway for the lower end of said bar and said bar capable of being locked through the arm or through its free end in said guideway to thereby hold the shutter in its open and closed positions.

4. A ventilator for railway cars comprising a rectangular frame having a chamber for the passage of air, said chamber having a restricted opening, a rockable shutter mounted beneath said opening, guideways centrally of the frame, a bar having a trunnion at one end slidably mounted in said guideways, and means at the end of the guideways to pre-

vent said bar from leaving said guideways, and the guideways and bar provided with openings whereby the bar may be locked to hold the shutter in either of its open or closed positions.

5. A ventilator for railway cars comprising a frame having a closed back and open through its lower front portion and through its upper portion, a shutter mounted in front of said opening to thereby open and close the passageway, a bar connected to said shutter, said bar provided with a trunnion at one end, guideways in said frame, means for locking the trunnion when at the lower end of said guideways to thereby hold the shutter in the closed position, and means for locking the bar when the trunnion is at the upper end of said guideways to thereby hold the shutter in its open position.

6. A ventilator for freight cars comprising a frame, projections out beyond the normal face of the frame adapted to fit within the siding of a freight car and the remainder of the frame adapted to fit within the freight car, the lower front face of the frame being open and the top of the frame also being open to provide a passageway through the frame, a rockable shutter within said frame and adapted to open and close said passageway, a locking bar connected with said shutter and said locking bar capable of being moved from the lower edge of the frame up within the same to thereby help support the shutter, and means for locking the bar in either of its several positions to thereby lock the shutter in its open and closed positions.

7. A ventilator for freight cars comprising a frame, said frame having a passage for air therethrough and a restricted opening, a rockable shutter in front of said opening to thereby open and close the same, guideways in said frame, a bar provided with a trunnion movable in said guideways and held against accidental removal in said guideways, means for locking the bar at either of two points in said guideways to thereby lock the shutter in its open or closed position.

8. A ventilator comprising a box-like frame open at its top, walls extending beyond the box-like portion and said walls adapted to be bolted to the inner siding of a car, means on the front face projecting beyond said walls and adapted to fit within an opening in the siding of a freight car, a passageway through the front face of the frame and outwardly through the top of the frame, a rockable shutter mounted in said passageway for opening and closing the same, a bar connected to the said shutter, guideways formed along the inner lower surface of said frame, said bar movable in said guideways, and means for locking the bar and the shutter when the shutter is in its open or closed position.

9. A ventilator comprising a box-like

frame open at its top, additional walls formed with said frame and adapted to be bolted to the siding of a freight car, said frame having a passageway formed therein, a shutter for opening and closing said passageway, guideways extending up the inner lower surface of said frame, lips on the outer end of said guideways, a bar pivotally connected to one edge of the shutter, said bar having a trunnion on its opposite end and a downwardly extending arm, the said arm and the said trunnion respectively provided with an opening therethrough and said guideways provided with an opening therethrough whereby the said arm or the said trunnion may be pinned when at the lower end of said guideway to thereby hold the shutter in an open or closed position.

10. A ventilator for grain cars comprising a frame, said frame opening through the top and out through its face, a screen in said frame, the said opening having a shutter in front thereof, means for operating the shutter comprising a bar, guideways in said frame, the rear end of the bar movable in said guideway, said bar helping to retain the shutter in its open and closed positions, and means for locking the bar when the shutter is in its open and closed positions.

11. A ventilator for freight cars comprising a frame box-like in structure open at its top, guideways formed in the bottom of said frame, a bar having a trunnion movably supported in said guideways, said bar having an arm projecting from its lower portion, a rockable shutter in said frame, the outer end of the bar being secured to said shutter, and means for locking the trunnion at the lower end of said guideway and for locking the bar when the trunnion is at the upper end of said guideways.

12. A ventilator for freight cars comprising a frame with a passageway therethrough, a rockable shutter for opening and closing said passageway, a bar connected with said shutter and extending horizontally within said frame when the shutter is in its open position and substantially vertical when the shutter is in its closed position, and means for locking the bar and likewise the shutter in both its open and closed positions.

13. A ventilator for freight cars comprising a frame with a passageway extending upwardly therethrough, a shutter for opening and closing said passageway, a three-legged bar having one leg connected to said shutter and the other two of said legs lockable in said frame to thereby hold the shutter in its open or closed position.

14. A ventilator comprising a frame having a passageway therethrough, a shutter rockably mounted in said passageway, guideways in said frame, a bar connected at one end to said shutter, the rear end of the bar slidably in said guideways, means at the top

of the guideways for limiting the upward movement of the inner end of the bar, means at the lower end of the guideways for limiting the outward movement of the bar to thereby respectively limit the downward movement of said shutter and to prevent the bar from leaving said guideways.

15. A ventilator for a freight car comprising a frame, a passageway up therethrough, a shutter for opening and closing said passageway, a bar connected to said shutter, a guideway in said frame, the said bar mounted in said guideway, means at the upper end of said guideway for limiting the movement of said bar and thus limit the outward opening movement of said shutter, means at the lower end of said guideway for limiting the outward movement of said bar to thereby hold the shutter in its open or closed position, and means for locking the shutter in its open and closed positions.

16. A ventilator for freight cars comprising a frame open at its bottom and unrestricted at its opening, said frame provided with a passageway connecting with said opening, an integral shutter in the said opening adapted to open and close said passageway, the passageway above the shutter being restricted to form a horizontal seat for a screen, a screen on said seat and the cross-sectional area of the passageway above the screen being greater than the cross-sectional area of the restricted portion just below the screen.

In testimony whereof I affix my signature.
